UNITED STATES PATENT OFFICE

GEORGE W. SWIFT, JR., OF BORDENTOWN, NEW JERSEY, ASSIGNOR TO GEORGE W. SWIFT, JR., INC., OF BORDENTOWN, NEW JERSEY, A CORPORATION OF NEW JERSEY

VENTILATED CUSHION PACKING

Application filed April 27, 1929. Serial No. 358,513.

This invention relates to cushion packings employed in packing cases for the shipment and handling of fragile articles, and has for its object to provide a cushion packing of improved construction that will simplify its manufacture, facilitate its manipulation, and which will afford enhanced protection for radio tubes, electric light bulbs, dry ice, and other fragile articles which are to be shipped from one place to another in suitable packing containers.

One purpose of my invention is to provide improved ventilation in packing containers employed for the shipment of eggs, or for the so-called dry-ice shipment of perishable commodities.

In respect to certain constructional details, my present invention constitutes an improvement on my copending application, Serial No. 347,891, which was filed in the United States Patent Office under date of March 18, 1929.

Another purpose of the present invention is to provide an improved cushion packing for dry ice, which requires a free circulation of air for maintaining a low temperature in and around a commodity which is being stored or shipped in a container cooled by dry ice. For this purpose, my present invention contemplates a corrugated cushion packing of improved construction which by means of relatively large corrugations and air spaces provided thereby, adapts said packing to serve as a lining for the containers in which the commodity is stored or shipped. Thus, my invention contemplates an arrangement of the corrugated cushion packing around the inner walls of a container in such a way as to permit the circulation of cold air and thereby to facilitate refrigeration. Reduced friction, due to the larger corrugations and larger air spaces, enhances this style of packing for dry-ice shipments.

While fragile articles are protected against rupture or puncture from the outside of a container which is provided with an inner wall liner of the character referred to, said liner can be more economically manufactured than other liners heretofore employed

for similar purposes; is lighter in weight; and gives greater protection to the encased contents against undue vibration and damage resulting therefrom.

Specific objects of invention will be understood from the specification, and the details relating thereto will be recited in the appended claims.

The drawings illustrate my invention in an adaptation to a packing-case for eggs.

Figure 1 is a fragmentary vertical section of an egg-case provided with one form of my improved cushion-packing.

Figure 2 is an enlarged fragmentary top plan view of the bottom cushion-packing removed.

Figure 3 is a fragmentary section on the line 3—3, of Figure 2.

Figure 4 is a fragmentary section on the line 4—4, of Figure 2; and

Figure 5 is a fragmentary section similar to Figure 3, showing a modified construction of the cushion-packing.

According to the embodiment of my invention, shown on the drawings, my improved cushion-packing is applied only to the top and bottom walls of the packing case, but for many uses it is desirable to employ my improved corrugated cushion packing as an outer liner around the inner wall of a shipping container. In its adaptation to an egg case, my improved cushion packing comprises a combined filler flat and cushion flat formed into a single packing member in which a central body or flat web portion is provided on one face with a corrugated web or webs having corrugations of relatively small size and on the other face thereof, is provided with a corrugated web having corrugations of relatively large size. The smaller corrugations are preferably embodied in laterally-spaced strips and the corrugations of each strip are preferably parted into groups in such a way that the intervening spaces extending transversely and longitudinally between the several groups, may be adapted to interlock with the vertically-arranged cell-forming partitions. The relatively larger corrugations on the opposite side of the flat web portion, are made of

sufficient size to fill in the space usually occupied by the cushion pads of old well-known construction and are preferably made to extend entirely across the flat web portion and 5 parallel to the smaller corrugations of the laterally-spaced strips. Furthermore, the larger corrugations are so arranged that the flat spaces between the groups of smaller corrugations of the laterally-spaced strips, 10 are directly supported by the inner bends of some of the larger corrugations on the opposite side of the flat web while the longitudinal flat spaces between said strips are directly reenforced by the successive inner 15 bends of all of the larger corrugations. It will be understood from this description that when the cushion flat is arranged in a packing case with the larger corrugations presented outwardly against the boards of said 20 packing case, the larger corrugations will constitute arched supports against which the burden of the packing case is effectively cushioned.

In Figure 1 of the drawings, the lower 25 portion of one end of an egg-case is shown, said egg-case having an end wall 1 reenforced at the bottom by a transverse strip 2 and a transverse partition 3. Arranged across the bottom edges of the end wall 1 and the trans- 30 verse partition 3 are laterally-spaced longitudinal strips 4 which provide ventilating slots in the top and bottom walls of the egg-case.

Extending over the inside bottom wall of 35 the egg-case compartment, as shown in Figure 1, is a cushion packing in which the central body or flat web portion consists of a single layer of cardboard or the like, a corrugated web 6 provided with corrugations of 40 relatively large size being secured to the under surface thereof, and a plurality of laterally-spaced corrugated strips 7 having corrugations of relatively small size, being secured to the upper surface thereof. As shown 45 in Figure 1, the relatively large corrugations in the corrugated web 6 are arranged transversely across the longitudinal slots formed between the laterally-spaced strips 4, the crown portions of said corrugations being presented downwardly in such a way as to 50 form ventilating galleries 8 extending from side to side of the egg-case and in open communication with the outside air through the longitudinal slots above referred to. As 55 shown in Figures 2 and 3, the relatively small corrugations of each of the laterally-spaced strips 7 are arranged in groups 9, the corrugations of one group being separated from the corrugations of an adjacent group by 60 means of flat bands 10. The grooves or corridors 11 which extend between adjacently disposed strips 7, together with the flat bands 10 which are alined transversely of the cushion packing, constitute depressions or seats 65 for the lower edges of partition walls or fill-

ers 12. Surmounting the upper edges of said partition walls 12 are filler flats 13, the partitions 12 and filler flats 13 being arranged in recurring series to the upper cushion packing which is inverted with respect to the lower cushion packing so that the upwardly-presented corrugations will be arranged transversely to the longitudinal ventilating slots for permitting a free passage of the air. By means of suitable ventilating openings or channels through and around the successive tiers of egg-containing compartments such, for example, as those shown and described in my above-identified copending application, Serial No. 347,891, a free circulation of air may be maintained throughout the interior of the shipping case.

According to the modified form of my improved cushion packing shown in Figure 5 of the drawings, the flat central body or flat web portion may comprise two separately constructed layers 14 and 15 of cardboard or other suitable material, the upper one of said layers having the laterally-spaced corrugated ribbons or strips 16 with relatively small corrugations applied thereto, and the lower one of said layers having the corrugated web 17 with relatively large corrugations applied thereto preliminarily to the fastening of said layers together to form the flat central web. As shown in Figure 5, the laterally-spaced strips 16 are provided with relatively small corrugations while the web 17 is provided with relatively large corrugations. According to this embodiment of my invention, the manufacturing operations may be simplified by avoiding the necessity of applying the corrugated web and strips to opposite sides of the same sheet in the same machine. Thus, the corrugated strips 7 may be secured to one sheet and the corrugated web 17 may be secured to another sheet after which said sheets may be secured together to form the combined filler and cushion packing. It furthermore simplifies the manufacturing operations in some cases in which thinner board may be employed for the backing or liner sheets and afterward combined to provide the central body or flat web portion of the desired stiffness and thickness.

I claim:—

1. A combined cushion pad and filler flat for packing cases, said combined cushion pad and filler flat comprising a central flat web, laterally-spaced strips secured to one surface of said flat web and provided with relatively small corrugations, the relatively small corrugations of each strip being parted into separate cell groups, and a corrugated web provided with relatively large corrugations and extending continuously and entirely across and secured to the opposite surface of said central flat web, said relatively large corrugations being adapted to form stiffening ribs for the central flat web along and transverse

to the relatively weak spaces extending between the cell-groups of relatively small corrugations on the opposite side of said central flat web.

5. 2. A combined filler and cushion flat for egg-cases comprising a flat central web, corrugated webs mounted on opposite faces of said flat central web, the corrugations on the upper face of said flat central webs being 10 of relatively small size and parted into groups corresponding respectively to the cells formed by the intersecting partitions of an egg-case, and the corrugations on the under face of said flat central web being of relatively 15 large size and comprised in a single corrugated web adapted to fill the cushioning space between the flat central web and the outer wall of said egg-case, said relatively 20 larger corrugations extending from one edge to the other of said flat central web for forming 25 a rigid structure between opposite side walls of the egg-case, the successive inner bends of the relatively large corrugations being arranged opposite to the parting lines between 30 the groups of smaller corrugations in said egg-cells or centrally with respect to said groups.

3. In a combined filler and cushion flat, the combination with a flat central web, of a plurality of laterally-spaced corrugated ribbons secured to one face of said flat central web, each of said corrugated ribbons being provided with relatively smaller corrugations parted into groups corresponding respectively 35 to the cells formed by the intersecting partitions of an egg-case, and a corrugated web secured to the other face of said flat central web, said corrugated web having relatively 40 larger corrugations extending from one edge to the other of said flat central web and transversely across the partition-seating galleries formed between the laterally-spaced ribbons, said larger corrugations having their inner bends arranged oppositely and centrally with 45 respect to the corrugated groups of the laterally-spaced corrugated ribbons or in alignment with and opposite to the parting lines between said groups.

4. In an egg case the combination with an 50 outer case provided with rigid walls, of a combined filler and cushion flat arranged between an outside wall of said egg-case and the edges of cell-forming partitions spaced from said outside wall, said filler and cushion 55 flat comprising a central flat web provided on its inwardly-presented surface with relatively smaller corrugations parted into groups corresponding respectively to the cells formed by said partitions, and on its outwardly-presented surface with a single corrugated web having relatively larger corrugations forming a cushion between the central flat web and the outer wall of the egg-case, said relatively larger corrugations on 60 the outwardly-presented side of said central

flat web having some of its inner bends arranged to reinforce the central flat web along the parting spaces between the cell groups of smaller corrugations in one direction and all of said relatively larger corrugations extending from one edge to the other of said flat central web and reinforcing said central flat web across the parting spaces between the cell groups of smaller corrugations in the other direction. 70

5. In a cushion packing for egg-cases, the combination with a flat central web adapted to be arranged within and spaced from an outer wall of an egg-case, of a plurality of corrugated ribbons spaced from each other 80 and from the opposite parallel edges of said flat central web on the inwardly-presented face thereof, the corrugations in each of said corrugated ribbons being parted into groups corresponding respectively to the cells formed by the intersecting partitions of said egg-case, and a corrugated web secured to the outwardly-presented face of said flat central web and having its corrugations extending continuously from one of said parallel edges 90 to the other of said flat central web, portions of said corrugated web and of said flat central web being extended beyond the outermost partitions and into abutment with the walls of said egg-case on all sides. 95

6. In an egg-case, the combination with a flat central web adapted to be arranged within and spaced from an inner wall of said egg-case, of a plurality of laterally-spaced corrugated ribbons spaced from each other and from the opposite parallel edges of said flat central web on the inwardly-presented face thereof, each of said corrugated ribbons being provided with relatively smaller corrugations parted into groups corresponding respectively to the cells formed by the intersecting partitions of said egg-case, and a corrugated web secured to the outwardly-presented face of said flat central web and having relatively larger corrugations extending 100 from one edge to the other of said flat central web and adapted to fill the usual cushion packing space between said inner face of the egg-case and the flat central web, said relatively 105 larger corrugations of the corrugated web being extended across said flat central web from one of said parallel edges to the other. 110

7. In a cushion packing for egg-cases, the combination with a flat central web adapted to be arranged within and spaced from one of the walls of an egg-case, of a plurality of laterally-spaced corrugated ribbons secured to the inwardly-presented face of said flat central web, each of said corrugated ribbons being provided with relatively smaller corrugations parted into groups corresponding respectively to the cells formed by the intersecting partitions of said egg-case, and a corrugated web secured to the outwardly-presented 120 125 130

face of said flat central web and having relatively larger corrugations extending from one edge to the other of said flat central web across the partition-seating galleries formed 5 between the laterally-spaced ribbons on the inwardly-presented face of said flat central web, said relatively larger corrugations being suitably proportioned and arranged to locate every other one of the inner bends 10 thereof opposite to and in vertical alinement with the cell-forming partitions transverse to the laterally-spaced corrugated ribbons and with the intermediately disposed inner bends of said relatively larger corrugations centrally arranged with respect to said cell 15 groups of smaller corrugations.
